UNITED STATES PATENT OFFICE

2,428,423

SIGNAL FOR RURAL MAIL BOXES

Wendell J. Hurban, Cleveland, Ohio

Application April 26, 1946, Serial No. 665,267

2 Claims. (Cl. 232—35)

1

This invention relates to improvements in signals for rural mail boxes.

My object is to supply a simple and inexpensive mechanism for signaling to rural mail box users that mail matter has been deposited in their mail box.

Also, my object is to construct a signal which will be an attachment to any standard rural mail box.

In my drawing—

Fig. 1 is a fragmentary side view of a rural mail box showing signal trapped down against the mail box by the door flange; Fig. 2 is a front elevation of the same; Fig. 3 is an enlarged drawing of the signal itself in upright signaling position; Fig. 4 is a cross section of same on a line 4—4, Fig. 3; and Fig. 5 is an enlarged top view showing method of attachment, on a line 5—5, Fig. 1.

I construct this signaling mechanism by cutting a piece of sheet metal into a square shape 6, Fig. 3, and to achieve a diamond shape in the upright position, I affix one corner 7 to one end of a coil spring 8, the other end of the coil spring I affix to a metal base 9 projecting laterally into a point 10.

On the square of sheet metal I paint a brightly colored spot 19 on a dark background, for the sake of good visibility.

The attachment to the mail box is accomplished by forcing the pointed base 10, Figures 3 and 5, into the crack 11 between the riveted part of the catchbar 12 and top of mail box 13.

It is operated as follows: When the door 14, Figures 1 and 2, of the mail box is closed, the square of sheet metal 6 is pulled down and one of the corners 15 is inserted between the door flange 16 and side of box 13. There it stays trapped until the door 18 is opened and then the signal springs into an upright position 17 as an

2

indication that mail matter has been deposited for the tenant.

Therefore, I claim:

- 5 1. In an attachment for rural mail boxes, a visible member being held above the mail box in an upright displaying position by being connected to one end of a helical spring, said spring providing flexibility for said visible member to be drawn down and turned in any direction convenient for restraining same in a non-displaying position, the other end of said helical spring being connected to a base for support, said base having a lateral extension ending in a point providing means for attachment to a mail box.
- 10 15 2. In an attachment for rural mail boxes having a catchbar riveted to the top, a visible member being held above the mail box in an upright displaying position by being connected to one end of a helical spring, said spring providing flexibility for said visible member to be drawn down and turned in any direction convenient for restraining same in a non-displaying position, the other end of said helical spring being connected to a base for support, said base having a lateral extension by means of which the attachment is kept affixed under the catchbar between the rivets on top of the mail box.
- 20 25

WENDELL J. HURBAN.
